UNITED STATES PATENT OFFICE.

CHARLES A. RINKER, OF GALESBURG, ILLINOIS.

BUNCH FORMER.

Application filed April 7, 1925. Serial No. 21,392.

This invention relates to a machine for use in the manufacture of cigars and it is, more especially, a machine for forming bunches and conveying them to the rollers.

5 One of the objects of the invention is to provide a machine of this character which will not only properly compress and shape the bunches but will also trim off both ends of the bunch prior to the delivery thereof from the machine.

10 Another object is to provide a bunch former which can be operated at high speed, does not require the use of an experienced operator, and which can be used with or without other bunching devices, thereby to perfect the bunches.

15 A still further object is to provide a machine which reduces the amount of binder, filler and wrapper necessary to produce a finished cigar, thereby effecting a considerable saving in production.

20 Another object is to provide a cigar buncher adjustable to form cigars of different sizes and which not only places the bunches under desired pressure during the shaping operation but also automatically dislodges the bunches successively so as to deliver them readily to the roller.

25 A further object is to provide a machine the operation of which is constantly under the control of the person feeding it so that the speed of operation will depend upon the speed of the operator.

30 With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

35 In the accompanying drawings the preferred form of the invention has been shown.

In said drawings,

Figure 1 is a side elevation of the machine.

Figure 2 is a vertical longitudinal section through the conveyor portion thereof and the parts cooperating therewith.

40 Figure 3 is an enlarged section on line 3-3 Figure 1.

Figure 4 is an enlarged section on line 4-4 Figure 2.

45 Figure 5 is an enlarged section on line 5-5 Figure 2.

Figure 6 is a perspective view of one of the forms.

Figure 7 is a perspective view of one of the ejectors used in the forms. 60

Figure 8 is a central transverse section through one of the forms.

Figure 9 is a plan view of the ejector operating lever.

55 Referring to the figures by characters of reference 1 designates the supporting frame of the machine in which are journaled transverse shafts 2 each of which carries a pair of sprocket wheels 3. One of the shafts 2 has a sprocket 4 adapted to be driven in any suitable manner. For example a chain 5 70

engaging said sprocket may receive motion from a sprocket 6 secured to a shaft 7 which, in turn, receives motion through sprockets 8 and 9 and a chain 10 from an electric motor 75

11. The operation of this motor can be controlled by a switch 12 including a foot lever or treadle 13 located at the feed end of the machine. Frame 1 supports, at the feed end 80 a table 14 for use by the operator and another table 15 is supported by the other end portion of the frame 1 for the cigar rollers.

An elongated table 16 is extended between the sprockets 3 of each pair and has bearings 17 through which the shafts 2 extend, 85 these shafts being arranged transversely of the table. Secured to and extending laterally beyond and supporting the table 16 are cross members 18 provided with upstanding rods 19 extending through the ends of cross 90 strips 20 and adjustably connected to them by nuts 21 engaging the upper and lower faces of the cross strips. An elongated pressure plate 22 is extended under and secured to the cross strips 20 and secured to the bottom of this plate above the space between the sprockets 3 at the feed end of the machine is a closing tongue 23 which is inclined 95 downwardly toward table 14 and has an upturned free end forming an abutment 24. A 100 spring 25 is interposed between tongue 23 and plate 22 and serves to hold the tongue 23 yieldingly pressed downwardly.

105 Mounted on the side portions of the table 16 are supporting frames 26 on which are secured parallel rails 27 each of which has an inwardly extending flange 28. These rails are parallel with the plate 22 and extend close to but are spaced from the sprockets 3. An endless conveyor is used in connection 110 with the sprockets 3 and is formed of connecting links 29 which engage the hooked

ends 30 of strips 31 extending from the ends of trough or box like containers 32. Thus the conveyor or belt formed in this manner will be properly engaged by the sprockets 5 and will be actuated thereby whenever power is applied.

Each container 32 is open at its ends to receive a block 33 in the outer face of which is formed a longitudinal recess 34 so shaped 10 at the bottom and sides as to properly shape the lower half of a cigar filler when compressed within the form. The recess is open at its ends, as shown at 35 and the top of the recess is adapted to receive a movable form member 36 which, when fitted within the recess 34 will shape the upper half of the filler. This form member 36 is secured to one end 15 of a yoke 37 having a flanged extension at its other end, as shown at 38. This yoke is pivotally connected at 39 to the advancing side of the container 38 and a spring 40 is located at the pivot for holding the form member 36 normally removed from recess 34.

Slots 41 are formed in the bottoms of the 25 recesses 34 and each slot has ears 42 slidably mounted therein. These ears extend from an arcuate ejecting plate 43 made up of oppositely extending wings as shown particularly in Figure 7. A pin 44 is extended 30 from each ejecting plate through the bottom of the block 33 and container 32 and has a head 45 at its free end. A spring 46 bears against this head and serves to hold the ejecting plate 43 normally flush with the bottom of recess 34.

Arms 47 are extended at right angles to the bottom of each container 32 and have outturned ends carrying rollers 48.

The plate 22 does not entirely bridge the 40 space between the shafts 2 but terminates at one end in advance of the sprockets at the delivery end of the machine. An ejecting lever 49 is located under the rails 27 and has laterally extending arms 50 between its ends 45 provided with depending ears 51 pivotally connected to the frame 26 as shown particularly in Figure 2. One end of this lever is inclined upwardly and toward the feed end of the machine, said end portion being down-turned to provide a deflecting tongue 52. The other end of the lever is extended upwardly toward the delivery end of the machine and has a head 53 beneath but close to the path of those containers 32 travelling 50 toward the delivery end of the machine. The lever is so proportioned and located that when the pin 44 of one form arrives in position above head 53 the container 32 of another form will come against and deflect 55 tongue 52 so as to cause the head 53 to thrust upwardly against the head 45 of the pin 44 thereabove, thereby to elevate or dislodge the filler contained within the form in which the pin is mounted.

60 The operator, who is the bunch breaker, is

located at the feed table 14 and this operator bunches the filler in one hand and applies thereto just enough binder to properly encase the bunch. This bunch is then placed in the form block 33 positioned at *a* in Figures 1 and 2. The machine is then started by means of the treadle 13 until another form is brought to position *a*. This second form block is filled and the same operation is repeated, the machine receiving an intermittent motion due to the starting and stopping of the motor. As soon as the machine is started the form block which has just been filled at *a* passes under the tongue 23 which, being engaged by yoke 37, causes said yoke 70 to swing against the action of spring 40 and bring the movable former 36 into the recess 34. Thus the bunch will be compressed and held in proper shape as long as yoke 37 is in engagement with the bottom of plate 22. As 75 the forms travel beneath the plate 22 they are brought successively between knives 54 suspended from the cross strip 20 located nearest the delivery end of the machine. Each of these knives has a V-shaped slot 55 80 extending thereinto from that edge nearest the feed end of the machine and the walls of these slots are sharpened. Thus as a form passes between the knives any portions of the bunch projecting beyond the open 85 ends 35 of recess 34 will be directed into the slots 55 and be severed by the walls of the slots. As each form passes from under plate 22 at *b* in Figures 1 and 2 the spring 40 will cause the movable form member 36 90 to swing out of recess 34, this movement continuing until extension 38 comes against the side of container 32. As each form arrives 95 in position above the head 53 another form actuates the lever 49 to shift the ejector plate 100 43 and dislodge the bunch. Thus when the form is brought to a partly inverted position above table 15 the bunch will be delivered therefrom on to the table where the 105 wrapper can be applied in the usual or any 110 preferred manner.

By mounting the pressure plate 22 adjustably, it becomes possible to vary the pressure exerted by the form members upon the bunches therebetween.

Obviously the forms can be of different lengths and can have recesses of different sizes so that cigars of different shapes and sizes can be produced. The knives 54 are provided with clips 56 which clamp upon the cross strip 20 on which they are mounted, thereby enabling the knives to be adjusted for use in connection with forms of different lengths.

What is claimed is:

1. In a cigar buncher a conveyor, forms carried thereby having open ended bunch receiving recesses, movable form members adjacent to but normally outside of the recesses, means operated by the movement of 125

the conveyor for shifting the movable form members into the recesses to compress bunches therein, and cutting elements cooperating with the ends of the recessed forms 5 for severing material projecting from the open ends of the recesses.

2. In a cigar buncher an endless conveyor, a pressure member adjacent thereto, bunch receiving recessed form members 10 movable with the conveyor, form members movably mounted relative to the recessed members and normally located out of the recesses, cooperating means upon the pressure member and the movable form members 15 for directing said members into the recesses to compress bunches therein and to maintain the bunches under pressure during a portion of the travel of the conveyor, an ejecting member in each recessed form, and means 20 operated by each form for actuating the ejecting member of another form.

3. In a cigar buncher a pressure member, form members arranged in pairs, one member of each of said pairs being movable successively into engagement with the pressure member to compress a bunch between the form members of each pair and maintain a plurality of bunches under pressure, means 25 for automatically separating the form member of each pair successively while moving out of engagement with the pressure member, and means compressible by a form member of one pair for lifting a compressed bunch from the separated form members of another 30 pair.

4. In a cigar buncher the combination with an endless conveyor and cooperating bunch compressing forms normally spaced apart, of spaced knives, a pressure member, and 40 means for actuating the conveyor to successively close together the cooperating forms and direct the forms between the knives.

5. In a cigar buncher a conveyor including a container having open ends, a recessed bunch receiving block removably seated in the container, a form member movable relative to the container and normally outside of the recess, an elongated pressure member adjustable relative to the conveyor and extending longitudinally thereof, and means 50 movable with the conveyor for movably engaging the pressure member to direct the movable form member into the recessed block and maintain it in the recess during a portion of the movement of the block with the conveyor.

6. In a cigar buncher an endless conveyor,

separate pairs of relatively movable form members movable with the conveyor and normally spaced apart yieldingly, fixed 60 means for holding the form members closed together to hold a bunch under compression during a portion of the movement of the conveyor, a spring restrained ejecting element carried by one form member of each 65 pair, and means operated by one form member of each pair for actuating the ejecting element of a form member of another pair.

7. In a cigar buncher an endless conveyor, a pressure member, laterally adjustable 70 knives supported by the pressure member, cooperating bunch compressing forms movable with the conveyor between the knives and along the pressure member, one of said forms having a bunch receiving recess with 75 open ends, and means carried by the other form for cooperation with the pressure member to direct said form into the recess to compress the bunch therein.

8. In a cigar buncher an endless conveyor, 80 a pressure member, laterally adjustable knives supported by the pressure member, cooperating bunch compressing forms movable with the conveyor between the knives and along the pressure member, one of said 85 forms having a bunch receiving recess with open ends, and means carried by the other form for cooperation with the pressure member to direct said form into the recess to compress the bunch therein, and means for 90 adjusting the pressure member relative to the conveyor for varying the pressure upon the bunch in the recess.

9. In a cigar buncher a feed table, a delivery table, bunch receiving forms for conveying bunches from the feed table to the delivery table, and means for holding a plurality of bunches simultaneously under compression within the forms during said movement.

10. In a cigar buncher a feed table, a delivery table, bunch receiving forms for conveying bunches from the feed table to the delivery table, means operated by the movement of the forms for placing a plurality 105 of bunches therein under compression and maintaining them under compression during a portion of the movement from one table to the other, and means for successively lifting the bunches automatically within the 110 forms prior to reaching the delivery table.

In testimony that I claim the foregoing as my own, I have hereto affixed my signature.

CHARLES A. RINKER.
